UNITED STATES PATENT OFFICE.

OLIVER H. COURSON, OF MEMPHIS, TENNESSEE.

COMBINED RAIL-BRACE AND TIE-PLATE.

1,102,725.

Specification of Letters Patent.

Patented July 7, 1914.

Application filed April 12, 1912. Serial No. 690,406.

To all whom it may concern:

Be it known that I, OLIVER H. COURSON, a citizen of the United States, residing at Memphis, in the county of Shelby and State 5 of Tennessee, have invented certain new and useful Improvements in Combined Rail-Braces and Tie-Plates, of which the following is a specification.

My invention relates to rail braces, and 10 particularly to that class known as combined rail braces and tie plates.

The object of my invention is to provide a combined rail brace and tie plate for securing and laterally bracing the rails against 15 any force exerted laterally against the same, whereby the dangerous "spreading" of the rails, or any relative movement between the rails and ties, is absolutely prevented.

My invention contemplates the use of a 20 rail chair provided with members contacting with and grasping the rail and provided with integral members adapted for positive engagement with the side of a cross tie.

In describing my invention in detail, reference will be made to the accompanying 25 drawings forming a part of the specification, wherein like characters indicate corresponding parts in the different views, and in which:—

Figure 1 is a perspective view showing 30 my combined chair and tie plate secured in position on a tie, and supporting a rail. Fig. 2 is a top plan view of the device in position.

In the drawings 1 indicates a base or tie 35 plate, which preferably consists of a single piece of metal, such as wrought iron, bent upon itself upon one side to form a rail brace 2, and upon the other side to form the brace 3. Obviously the tie plate and brace 40 may be formed of separate pieces of material, but, for sake of economy and strength I prefer to form them integrally. The rail brace 2 is bent at an angle so as to conform 45 to the shape of the rail 4, and extends upwardly over the flange 5, and web 6 thereof, and preferably, although not necessarily, terminates in a head upon which rests the under surface of the head of the rail.

The plate 1 is provided upon either side, 50 with a plurality of laterally extending integral projections or spurs 7, provided with sharpened ends. These spurs 7 extend downwardly and inwardly and are adapted 55 to be forcibly driven into the side of the cross ties 8.

In manufacturing my device the flange 3 is formed vertically, and extends at right angles to the plate 1, and consequently parallel with the web 6 as shown in dotted lines 60 in Fig. 1.

In applying the device it is first placed 65 upon the tie 8, and the edge 9 of the rail flange inserted beneath the brace 2, until said edge contacts with the inner vertical 70 face of the brace 2. When in this position the opposite edge 10, of the rail flange 5, will pass the vertically disposed flange 3, and the whole rail flange will rest upon the plate 1. Spikes 11 are then driven into the 75 tie, between the edge 10, and the inner face of the flange 3, as shown in Fig. 2. The flange 3 is then forced downwardly and inwardly, until it rests upon the rail flange 5, covering the spikes 11 and contacting therewith. These flanges may be turned inwardly by hammering, or by machines. At 80 this time the spurs 7 extend outwardly and are curved backwardly, as shown in dotted lines in Fig. 1. The spurs are adapted to be 85 driven inwardly into the ties 8, or may be forced therein by machinery. Their position after entering the tie is plainly shown in Fig. 1.

It is to be noticed that the inner edges 12, 85 12 of the spurs 7 extend inwardly beneath the rail. This construction is of considerable importance, since the weight of the rail prevents the spurs 7 from "buckling" upwardly when the spurs are driven or forced 90 into the ties.

It will be obvious that when my device is 95 properly positioned, relative movement between the rail and the tie is impossible. The braces and spurs are made of metal of sufficient tensile strength to more than withstand all the strains which they will ever be called upon to bear. Moreover I absolutely dispense with all exposed spikes. The spikes 100 11 may be dispensed with if necessary, without materially affecting the efficiency of my device, although it is obvious that they assist in holding the rail. It is to be observed however, that said spikes are completely covered by the brace 3, and that their vertical movement is prevented thereby. The vertical movement of the rail holding spikes is materially assisted by water entering the holes adjacent the spike, causing a decay of the wood and consequent loosening of the spike. 110 The vibrations caused by rapidly moving trains causes the spikes to be partially drawn

from the holes, whereby a separation between the rails and ties is effected. My invention absolutely prevents this relative movement.

5 An important feature of my construction resides in the fact that the device is adapted for use upon ties of varying widths, and without any preliminary adjustment. Furthermore it is not necessary that the top of 10 the ties be absolutely level, as the natural spring of the rail will preserve a straight line.

My device is not only adapted for use upon wooden ties, but is especially fitted for 15 use upon ties constructed of metal or composition. In such cases the tie is provided with slots for the reception of the spurs 7.

Various modifications of my invention may be suggested to those skilled in the art, 20 but I reserve the right to make such various changes in the details of arrangement as fall within the scope of the appended 25 claims.

Having fully described my invention, 25 what I claim and desire to secure by Letters Patent is:

1. A combined tie plate and rail brace provided with members adapted to brace either 30 side of a rail and having bendable projections adapted to be driven into the sides of a cross-tie.

2. A combined tie plate and rail brace made of a single piece of material and provided with members adapted to brace either 35 side of a rail, and with bendable projections or spurs integral with the plate and adapted to being driven into either side of a cross-tie.

3. A tie plate and rail brace formed of a 40 single piece of metal, and having a plurality of integrally formed bendable projections adapted to be driven into the sides of a cross-tie.

4. A combined tie plate and rail brace 45 comprising a plate provided with braces adapted to engage a rail, and bendable projections adapted to be driven into the sides

of a tie, said projections extending under and partially supporting said rail.

5. The herein described improvement in 50 combined tie plates and rail braces, consisting of a plate provided on one side with an integral flange bent to the contour of and adapted to contact with a rail, and upon the other side with an upwardly extending 55 flange adapted to be bent downwardly to engage a rail, said plate being also provided with a plurality of projections adapted to be driven into the sides of a cross-tie.

6. The herein described improvement in 60 combined tie plates and rail braces, consisting of a plate provided on one side with an integral flange bent to the contour of and adapted to contact with a rail, and upon the other side with an upwardly extending 65 flange adapted to be bent downwardly to engage a rail, said plate being also provided with a plurality of projections adapted to be driven into the sides of a cross-tie, part of said projections extending longitudinally 70 under and being adapted to partially support said rail.

7. A combined tie plate and rail brace comprising one integral element a plate with braces adapted to engage a rail and 75 laterally extending projections at right angles to said braces and extended downwardly and inwardly to be forcibly driven into the sides of a cross-tie.

8. A combined tie plate and rail brace 80 comprising one integral element a plate with braces adapted to engage a rail and laterally extending projections at right angles to said braces and extended downwardly and inwardly to be forcibly driven 85 into the sides of a cross-tie, the inner edges of said projections being extended inwardly beneath the rail.

In testimony whereof I affix my signature in presence of two witnesses.

OLIVER H. COURSON.
